TIMER FOR INTERNAL COMBUSTION ENGINES

Myrl Ives and James D. La Bell, Flint, Mich.

Application February 19, 1937, Serial No. 126,718

15 Claims. (Cl. 200—30)

This invention relates to circuit makers and breakers and particularly to periodically operating devices of the type described intended primarily for ignition circuits.

5 It is a general object of the present invention to provide novel and improved circuit making and breaking apparatus for prolonging the life of the contacts and improving the operation thereof.

10 More particularly, it is an object of the invention to provide in a contact making and breaking device a pair of confronting contacts engageable by movement parallel to their contact faces, and in which, in addition to the movement for opening and closing the circuit, at least one of the contacts is caused to revolve about an axis eccentric to the other to continuously present different surfaces on the two contacts for engagement with each other.

15 An important feature of the invention resides in the provision of means for imparting circular movement to one of a pair of confronting contacts to maintain the contact surfaces uniform and clean.

20 Another feature of the invention resides in the provision, in confronting contacts, of means for imparting a circular or gyratory movement to one of the contacts and imparting to at least one of the contacts a rotary movement about its own axis, both of these mentioned movements being independent of that causing separation and engagement of the contacts.

25 Still another feature of the invention resides in the provision of ignition apparatus for automotive type internal combustion engines provided with a motor driven fan or operated in a substantial blast of air, and wherein means is provided driven by the air blast to maintain the contacts in good condition.

30 Other and further features and objects of the invention will be more apparent to those skilled in the art upon a consideration of the accompanying drawings and following specification wherein are disclosed several exemplary embodiments of the invention with the understanding that they can be so combined, modified or changed within the scope of the appended claims without departing from the spirit of the invention.

35 In said drawings:

40 Figure 1 is a plan view, with cover removed, of a circuit maker and breaker of the type commonly used for automotive ignition, the apparatus being modified by the addition of one embodiment of the present invention;

45 Figure 2 is a vertical section on broken line 2—2 of Figure 1;

50 Figure 3 is a fragmentary section on line 3—3 of Figure 1;

55 Figure 4 is a view similar to Figure 1 showing a further embodiment of the invention;

60 Figure 5 is a view similar to Figure 1 showing a third embodiment of the invention; and

65 Figure 6 is a view similar to Figure 1 showing a fourth embodiment of the invention. 10

The operation of automotive ignition apparatus under the present day demands for high speed, multiple cylinders, high spark voltage to overcome extreme compression ratios, and for long life without attention has resulted in severe conditions imposed upon the primary circuit breaker. It must handle heavy currents at extremely high speeds, and the contact points are thus subject to various defects known in the trade as "pitting", "knife edging" and the like, 20 which seem to result from misalignment of the contact points, improper facing of the points, and bouncing from high speed operation, and from other causes, but all produced primarily by the erosion of the arc formed every time the circuit is broken. In most cases the arc seems to burn or melt the metal from one contact and deposit it on the other, sometimes producing a deep crater in one and a corresponding peak on the other. The conditions are such that the rate 25 of growth of the one point is greater than the rate of cratering of the other, producing a continued reduction in the length of the gap between the contact points until finally the circuit is not completely broken and operation of the 30 motor ceases until the points are properly ground, filed, adjusted or replaced. 35

The present invention deals with apparatus for preventing to a large degree the difficulties enumerated above, and for maintaining the contact points in excellent condition over a long period of time. Primarily the invention is based on mechanism for continually presenting different portions of the confronting contacts to each other and for moving the contacts while 40 they are in engagement with each other to maintain the surfaces clean and smooth. 45

Referring first to Figures 1, 2 and 3, there is shown at 10 the more or less conventional housing of the usual automotive circuit breaker, which 50 housing usually carries the distributor cap which forms no part of the present invention and is not shown herein. This housing provides the bearing for a central shaft 11 driven at appropriate speed from some moving part of the motor and 55

carrying the cam 12 having one lobe for each cylinder to be fired. The device is provided with a pair of confronting contacts 14 and 15, the first one relatively stationary and the second one carried on the end of the so-called breaker arm 16 pivoted at 17 and spring pressed so that the cam follower 18 thereon rides on the surface of the cam 12 or at least is engaged by the lobes of the cam. Under the action of the spring the confronting contact points 14 and 15 are brought into engagement when the follower 18 is released by a cam lobe, and these points are separated by the action of the lobe on the follower, assuming an open circuit position such as shown in the drawings.

All of the above is conventional. The word, "points", as used in connection with the portions which engage to make and break the circuit is intended in its customarily used meaning and not in its true literal sense. In other words, the so-called points are actually cylindrical contact members having flat or substantially flat engaging surfaces.

The so-called stationary contact 14 is mounted on the end of a rod or shaft 20 which has a close but running fit in the eccentric bore 21 of the cylindrical sleeve 22 journalled in the elongated bearing 23 extending from the housing 24 of a small electric motor and supported by the housing 10.

An enlargement 25 near the contact end of the rod 20 forms a thrust bearing with the end of the sleeve 22 and a nut 26 on the opposite end of the shaft or rod holds it in position in the sleeve and adjusts its frictional relation thereto. The sleeve is arranged to be directly rotated by the armature of the motor. The motor is preferably arranged to be turned on and off with the ignition circuit.

The eccentricity of the sleeve bore is such that the contact point 14 is given a movement in a circular path, the radius of which is preferably less than the diameter of the opposite contact. This causes the two contacts to continually present changing surfaces to each other, but improvement results if the contact 14 is also given a true rotary movement about its own axis, and this is done by having the periphery of the head 25 on the rod suitably toothed or roughened. Due to its eccentric motion it is brought, once per revolution, into engagement with the tooth or dog 27 supported by the arm 28 from a suitable part of the casing 10. The shaft 20 is thus given a relative rotational movement in respect to the sleeve which carries it, and this movement can be considered as a true "rotation", using this word in its limited sense of meaning movement about its own axis. The other movement of the contact can be considered as "revolution", likewise used in its limited sense as meaning movement in an orbit about a central point or axis. It is, of course, immaterial which contact is revolved and which is rotated, but for the sake of convenience, it is best to have both motions imparted to the same contact as shown.

Adjustment for clearance between the contacts is obtained by means of the conical ended screws 29 threaded into the portion of the casing which receives the extended bearing 23. The ends of these screws take into conical notches in this part 23, which notches are spaced at less distance apart than the axes of the screws. By moving one screw inwardly and the other outwardly, longitudinal movement of the bearing 23 can be effected, as will be understood.

Where it is not desired to use an electric motor for driving the rotatable contact and where the ignition apparatus is mounted in a blast of air such as that which comes from the propeller of an aeroplane or from the cooling fan of an automobile or similar motor, resort may be had to the mechanism shown in Figure 4. Here the construction is substantially identical with that shown in Figure 1 except for the driving mechanism, and no reference will be had here to parts 10 which are common to both embodiments.

The shaft 20' which carries the relatively stationary contact mounts at its outer end a fan 35 having several blades. Likewise, the eccentric sleeve 22' mounts near its outer end a fan 36 of similar construction. If these fans are appropriately presented to the blast of air passing over the motor, as for instance from the fan F, they will be rotated thereby and impart to the relatively stationary contact 14' both rotation and revolution. It might be desirable to have these fans of reverse hand to insure against the shaft and sleeve moving in unison. At idling speeds of the motor, there may not be sufficient air blast to operate the fans 35 and 36, but this is of no serious consequence, for the worst that the breaker of the present invention can do is to operate at the best the conventional breaker can operate.

Figure 6 shows another way of obtaining rotary movement of the relatively stationary contact. In this construction the eccentric sleeve 22' is driven by a worm 48, which may be multiple threaded if desired, on the cam shaft 12' which engages with the worm wheel 44 on the sleeve 22'. This sleeve, in its eccentric bore, journals the shaft 29', as in Figure 1, which obtains its movement relative to the sleeve in the same manner, as shown. This construction will not give as rapid turning movement to the contact, but is entirely satisfactory where a self contained construction is desired.

In Figure 5 is shown an embodiment wherein the substantially stationary contact is given a gyratory movement, that is, its axis moves over the surface of a theoretical cone. To achieve this movement the relatively stationary contact 14' is mounted on the end of a rod 50 having intermediate its ends a spherical enlargement 51. This enlargement bears on one end of the coil spring 52, having its opposite end abutting shoulder 52' in the sleeve 53, mounted in any suitable manner, for instance, in the bushing 54, integral with the housing 10'. A hollow, exteriorly threaded sleeve 55 is adjustable to bear on the enlargement 51 to confine it between this sleeve and the spring 52 to form a universal bearing for the same and to provide for adjustment of the air gap between the contacts. The opposite end of the rod 50 is provided with a small ball 56 received in the eccentric bore 57 in the head 58 on the end of shaft 59 journalled in sleeve 60 mounted in bushing 54 and carrying on its outer end the fan 61. A suitable lubricant containing chamber 62 is provided along with oil passages, not shown, for lubricating the mechanism.

The operation of this device is quite similar to that of the others previously described except that the contacts, after some use, assume complementary surfaces of spherical sectors. It is believed that in operation the movement imparted which has been referred to as gyratory is such that there is a certain crawling action of the spherical enlargement 51 in its bearings which results in a slow rotation of the rod 50 about its 75

own axis, thereby achieving automatically the result obtained in the other forms of the invention by the addition of parts.

All forms of the invention provide very satisfactory service because only once in a great number of times will the same two portions on opposite contacts come into engagement so that there is no tendency for cratering, knife edging, or the like. The contacts achieve smooth, regular surfaces maintained throughout substantially their whole range, their life is materially prolonged, and the operation of the ignition equipment maintained at maximum efficiency for the whole life of the contacts.

Obviously the invention is not limited to ignition equipment with which it has been described for the sake of convenience, but can be applied to most any type of circuit closing mechanism where confronting contacts are used.

Having thus described the invention, what is claimed as new and desired to be secured by Letters Patent is:

1. A circuit maker and breaker for ignition systems comprising, in combination, a relatively stationary contact point, a confronting contact point movable to and from the first contact to control a circuit, means to rotate one of said contact points about its own axis and means to revolve one of said contact points about the axis of the other.

2. A circuit maker and breaker of the cam operated type for ignition systems comprising, in combination, a relatively stationary contact point, a breaker arm operable by the cam, a contact point carried by said arm in confronting relation to the first contact point and movable into and out of engagement therewith by the cam, means to revolve one of said contacts about the axis of the other on a radius less than the diameter of the other point to continually present different surfaces for contact to retain the surfaces of the points substantially uniform.

3. A circuit maker and breaker of the cam operated type for ignition systems comprising, in combination, a relatively stationary contact point, a breaker arm operable by the cam, a contact point carried by said arm in confronting relation to the first contact point and movable into and out of engagement therewith by the cam, means to revolve one of said contacts about the axis of the other on a radius less than the diameter of the other point, and means to rotate one of said contact points about its own axis at a speed independent of the speed of revolution.

4. A circuit maker and breaker of the cam operated type for ignition systems comprising, in combination, a relatively stationary contact point, a breaker arm operable by the cam, a contact point carried by said arm in confronting relation to the first contact point and movable into and out of engagement therewith by the cam, a circular shaft supporting said relatively stationary contact axially at one end thereof, a sleeve mounted for rotation, said sleeve having an eccentric bore journalling said shaft, and means to rotate said sleeve.

5. A circuit maker and breaker of the cam operated type for ignition systems comprising, in combination, a relatively stationary contact point, a breaker arm operable by the cam, a contact point carried by said arm in confronting relation to the first contact point and movable into and out of engagement therewith by the cam, a circular shaft supporting said relatively stationary contact axially at one end thereof, a sleeve

mounted for rotation, said sleeve having an eccentric bore journalling said shaft, means to rotate said sleeve, and means to rotate said shaft within said sleeve.

6. A circuit maker and breaker of the cam operated type for ignition systems comprising, in combination, a relatively stationary contact point, a breaker arm operable by the cam, a contact point carried by said arm in confronting relation to the first contact point and movable into and out of engagement therewith by the cam, a circular shaft supporting said relatively stationary contact axially at one end thereof, a sleeve mounted for rotation, said sleeve having an eccentric bore journalling said shaft, means to impart substantially steady rotation to said sleeve, and means actuated by the eccentricity of the shaft mounting to impart rotary movement to said shaft relative to said sleeve once per sleeve revolution.

7. A circuit maker and breaker of the cam operated type for ignition systems comprising, in combination, a relatively stationary contact point, a breaker arm operable by the cam, a contact point carried by said arm in confronting relation to the first contact point and movable into and out of engagement therewith by the cam, a circular shaft supporting said relatively stationary contact axially at one end thereof, a sleeve mounted for rotation, said sleeve having an eccentric bore journalling said shaft, a motor directly driving said sleeve, a toothed member on said shaft outside of said sleeve and a dog engageable by said member once per revolution of the sleeve to impart relative rotation to the sleeve and shaft.

8. A circuit maker and breaker of the cam operated type for ignition systems comprising, in combination, a relatively stationary contact point, a breaker arm operable by the cam, a contact point carried by said arm in confronting relation to the first contact point and movable into and out of engagement therewith by the cam, a circular shaft supporting said relatively stationary contact axially at one end thereof, a sleeve mounted for rotation, said sleeve having an eccentric bore journalling said shaft, a fan on said sleeve, a fan on said shaft, both said fans being exposed to a current of air whereby both are rotated to impart rotation and revolution to said relatively stationary contact.

9. An ignition interrupter for use with internal combustion engines operating in a current of air, including, in combination, a pair of confronting contacts, means to reciprocate one of said contacts to open and close a circuit, and means operable by said current of air to move said other contact in a substantially circular path solely to present new surfaces to the other contact.

10. An ignition interrupter for use with internal combustion engines operating in a current of air, including, in combination, a pair of confronting contacts, means to reciprocate one of said contacts to open and close a circuit, and means operable by said current of air to gyrate said other contact on a radius less than the diameter of the first contact.

11. A circuit interrupter for internal combustion engine ignition systems including, in combination, a pair of contacts, means to oscillate one of said contacts, means mounting the other contact to move in a circular path and a fan exposed to air moving by said interrupter to move said contact in its path.

12. A circuit interrupter for internal combustion engine ignition systems including, in combination, a pair of contacts, means to oscillate one of said contacts, means mounting the other contact to move in a circular path, a fan exposed to air moving by said interrupter to move said contact in its path, a second fan, and means connecting it to rotate said other contact about its own axis.
13. A circuit maker and breaker of the cam operated type for ignition systems comprising, in combination, a relatively stationary contact point, a breaker arm operable by the cam, a contact point carried by said arm in confronting relation to the first contact point and movable into and out of engagement therewith by the cam, a rod having a spherical enlargement remote from one end, means journaling said enlargement for universal movement of the rod including rotation, said first contact being carried at said end of said rod and means to actuate said rod to gyrate said contact.
14. A circuit maker and breaker of the cam operated type for ignition systems comprising, in combination, a relatively stationary contact point, a breaker arm operable by the cam, a contact point carried by said arm in confronting relation to the first contact point and movable into and out of engagement therewith by the cam, a rod fulcrumed intermediate its ends for universal movement, said first contact being carried at one end of said rod, and means to move the opposite end of said rod in a circular path asynchronous to the breaker arm movement.
15. A circuit maker and breaker of the cam operated type for ignition systems comprising, in combination, a relatively stationary contact point, a breaker arm operable by the cam, a contact point carried by said arm in confronting relation to the first contact point and movable into and out of engagement therewith by the cam, a rod having a spherical enlargement remote from one end, means journaling said enlargement for universal movement of the rod including rotation, said first contact being carried at said end of said rod and means to actuate said rod to gyrate said contact.

16. A contact maker and breaker including two contact members having substantially flat faces for engagement with each other by movement substantially parallel to said faces, means to rotate one of said contacts substantially about the center of its face and means to revolve one of said contacts about an axis eccentric to said center.

17. A contact maker and breaker including two contact members having substantially flat faces for engagement with each other by movement substantially parallel to said faces, means to rotate one of said contacts substantially about the center of its face and means to revolve one of said contacts about an axis eccentric to said center.
